(57) **CLAIM**

The ornamental design for a transaction card having trapezoidal edge feature, as shown and described.

DESCRIPTION

The present application is filed contemporaneously with U.S. Design patent application Ser. No. 29/801,997, entitled Chipped or Chipless Transaction Card Having Triangular Edge Feature, the entire disclosure of which is hereby incorporated by reference herein.

FIG. 1 is a perspective view of the first embodiment of the transaction card having trapezoidal edge feature showing our design;

FIG. 2 is a plan view, the opposite plan view being a mirror image thereof;

FIG. 3 is an end view thereof;

FIG. 4 is a perspective view of a second embodiment thereof;

FIG. 5 is a plan view, the opposite plan view being a mirror image thereof;

FIG. 6 is an end view thereof;

FIG. 7 is a perspective view of a third embodiment thereof;

FIG. 8 is a plan view, the opposite plan view being a mirror image thereof; and,

FIG. 9 is an end view thereof.
